By Attorney

UNITED STATES PATENT OFFICE.

JESSE H. McMATH, OF CLEVELAND, OHIO.

DESIGN FOR A BADGE.

SPECIFICATION forming part of Design No. 18,015, dated January 10, 1888.

Application filed November 30, 1887. Serial No. 256,564. Term of patent 3½ years.

To all whom it may concern:

Be it known that I, JESSE H. McMATH, a citizen of the United States, residing at Cleveland, in the county of Cuyahoga and State of Ohio, have invented and produced a new and original Design for a Badge, of which the following is a specification, reference being had to the accompanying drawing, forming a part thereof.

10 The drawing forms a front view of my newly-designed badge, which is a shield having two hands grasped, as in the act of shaking hands, across its face, and within the grasped hands an olive branch pendent on the face of the said shield, a part of the bars on the face of the shield being obscured by the grasped hands, and pendent from the shield a canteen, on the face of which is an olive branch.

15 The leading features of my design consist of

the shield, grasped hands, and olive branch, 20 the wrist of the grasped hands extending beyond the edges of the shield.

Having thus described my invention, what I claim, and desire to secure by Letters Patent, is—

25 1. In a design for a badge, the body consisting of the shield, the grasped hands, and the olive branch within the grasped hands, substantially as set forth.

2. The design for a badge, consisting of the shield, the grasped hands, the olive branch within the grasped hands, and the canteen pendent from the shield and having an olive branch across its face, substantially as shown.

JESSE H. McMATH.
